SCREEN STRUCTURE

Truman L. Atkinson, Ludington, Mich.

Application September 15, 1947, Serial No. 774,010

3 Claims. (Cl. 160—328)

1

This invention relates to a screen structure. Screens are attached to or associated in numerous ways with window and other openings, particularly during the summer months when the windows are opened wholly or partly, for the exclusion of insects and the larger dirt particles.

In the present invention, a screen structure is provided of a very practical and economical form, wherein the owner of a house or building may buy the screen material and cut it in the lengths required for different dimensional lengths of windows to be screened, and install it on a window or windows, by means of attachments which I have devised, in a simple and ready manner. The attachments hereinafter fully shown and described include upper and lower edge strips to be connected at the upper and lower edges of a screen body of the proper length for a window, together with cooperating members which are attached at the upper ends of a window opening for a detachable connection of the border strip at the upper end of the screen section, and detachably and adjustably connect with the lower end screen members, to not only secure the screen in place, but tighten it and draw it taut with a filling of the window opening when the screen has been applied.

It is the primary object and purpose of the present invention to provide a screen structure and attachments for the screen material to make such novel screen structure as outlined, and one which is readily secured and attached in place for use at a window, whatever may be the length of the window. The widths of windows are generally standard and screen material in the regular standard widths is available.

An understanding of the invention may be had from the following description, taken in connection with the accompanying drawings, in which,

Fig. 1 is a vertical section through a window equipped with the screen structure of my invention,

Fig. 2 is an inner perspective view of the window with the screen attached,

Fig. 3 is a fragmentary vertical section, similar to Fig. 1, with the intermediate portion of the window frame structure broken away, illustrating the connection of the screen at its upper and lower ends more clearly, in enlarged form,

Fig. 4 is a perspective view of the upper connecting bracket of which a number may be used at the upper end of the screen,

Fig. 5 is a perspective view of the lower connecting and tensioning fixture, a number of which are to be mounted at the upper side of the window sill,

Fig. 6 is a fragmentary perspective view illustrating the upper end screen structure and the metal strip to be secured thereto, and

2

Fig. 7 is a similar perspective view of the metal strip members at the lower end of the screen body, the parts in Figs. 6 and 7 being separated from each other.

Like reference characters refer to like parts in the different figures of the drawings.

The window of a conventional form and structure will have a lower sill 1, an upper horizontal end 2 and vertical sides 3. At the inner sides of the sides 3, spaced parallel guide bars 4 are permanently attached for the vertical guiding of movable window sashes 5, which, in the usual manner, may be moved past each other to partly open the window. At the upper end of the window opening and at the under side of the upper side 2, similar transverse or horizontal bars 6 are secured, between which at least the outer window sash 5 is positioned at its upper end when the window is closed. The environment described is that of a conventional window, at the outer side of the opening of which the screen structure of my invention is to be installed.

At the lower side of the outer upper transverse bar 6, a number of metal brackets 7 are secured by screws, having outer ends formed into shallow hooks 8 which extend a short distance beyond the plane of the outer side of the bar 6 to which attached. Two of said bracket members 7, spaced apart, are shown, but the number which may be used is not limited to two, but may be increased if desired, though generally two of them will be all that are needed.

At the upper side of the lower sill 1, engaging and screen tensioning members are secured, in practice two in number. Each has a lower base 9 of flat metal, at its outer end portion turned outwardly in a vertical leg 10, as shown. At its inner end a second vertical leg 11 of less height extends upwardly, which at its upper edge has a projecting lug 12 (Fig. 5). The middle portion of the bottom or base 9 is offset upwardly, as shown, and through it a vertical screw 13 passes, the head of the screw coming underneath the lower side of the middle portion of the base 9.

The screw at its threaded upper end portion passes through a bar or lever 14, which has a longitudinal slot 15 for the screw 13 to pass through, and an opening 16 near its inner end through which the lug 12 on the leg 11 passes, thereby mounting the bar or lever 14 on the leg 11 to have limited pivotal movement. A washer 17 is located around the upper end portion of the screw 13 over the lever 14, and a thumb nut 18 is screwed onto the upper end portion of the screw.

The body 19 of screen material has a width substantially equal to the distance between the inner sides 3 of the window frame. Its length may be cut to be approximately the length 60 between the sill 1 and the upper side 2 of the

window frame. At the upper end of the screen 19, a bar made of thin sheet metal is located and secured. Said bar has an intermediate flat section 20 from which, at its upper edge, the metal is bent into a U-turn and terminates in a leg 21 parallel to and back of the upper part of the intermediate section 20. At the lower edge the metal is similarly return bent in a U-bend and upwardly in a leg 22. The upper edge portion of the screen 19 is gripped or clamped between said leg 22 and the intermediate portion 20, the screen being bent over the upper edge of the leg 22 and thence extending downwardly back thereof. In practice the upper border strip for the screen will have the leg 22 spaced from the intermediate portion 20 a distance such that the upper edge portions of the screen 19 may be readily inserted therein, after which the parts are clinched or hammered together to make a secure and permanent connection.

Associated with the lower end of the screen is a transverse U-shaped member of sheet metal having inner and outer vertical sides 24 and 25 integrally connected at their lower edges by a U-bend (Fig. 7). The outer side 25 extends above the inner side 24 and is formed longitudinally at its upper edge with a bead 26 substantially of semi-circular cross section, as shown. In the lower U-bend connecting the vertical sides 24 and 25, recesses 27 are cut of a depth sufficient for the passage of the base plate 9 of the lower fixtures used, whereby the outer upwardly extending legs 10 will be located at the outer side of the outer vertical leg 25. Similarly, the inner vertical legs 24 are notched or recessed with rectangular recesses 28, one for each of the levers 14, which in the installed screen will be positioned at their outer ends in vertical alinement with or partially entering such recesses 28.

At the lower end of the screen 19 an inverted U-shaped bar 29 of thin sheet metal is attached by turning the lower end portion 19 of the screen upwardly and to the rear of the body of the screen in a terminal section 30, which is received between the sides of the bar 29 and securely clamped thereto by clinching or hammering said sides together. Of course, the lower edge portion of the screen 19 may be inserted into the open edge of the bar 29 and the bar attached and thereafter the bar 29 turned through an arc of substantially 180 degrees to locate it in its inverted position with the body of the screen at the outer side of the outer legs of the U-bar 29.

The bar 29 secured to the screen body 19 is inserted in and received between the two legs 24 and 25 of the previously described sheet metal bar structure. The connecting bend between the outer and inner sides 24 lies against the upper side of the sill 1 and the outer side 25 against the vertical legs 10 of the lower fixtures used, preferably two in number. The free ends of the levers 14 are cut away and shaped to bear against the upper rounded edge of the U-shaped bar 29. By tightening the nuts 18 the bar 29 with the attached screen is forced downwardly between the sides 24 and 25 (Fig. 3) until the screen body 19 is properly tightened.

The structure described is very practical and useful, economically manufactured and easily installed. After the upper brackets 7 and the lower fixtures having bases 9 and levers 14 have

once been installed in place, they may be left on the window. The upper leg 21 seats in the hooks 8 of the bracket 7, as shown. The purchaser obtains the brackets 7, the lower fixtures, the upper screen bar having integral parts 20, 21 and 22, the screen attached lower bar 29 and the other bar having the sides 24 and 25. He mounts the brackets 7 and the lower fixtures on the window frame, attaches the lower bar 29 at the lower end of the screen body and the upper bar 20 at the upper end thereof, positions the sill-engaging U-bar in place, makes a hook connection of the upper bar with the brackets 7, inserts the lower bar 29 between the sides 24 and 25, then applies the levers 14 and tightens them by manual operation of the thumb nuts 18.

The window opening is filled and insures against insect entrance, while permitting desired ventilation.

The invention is defined in the appended claims and is to be considered comprehensive of all forms of structure coming within their scope.

I claim:

1. In a structure of the class described, a horizontal channel of a predetermined length open at its upper side having its lower closed side adapted to be located against a horizontal window sill, a tensioning member adapted to be permanently secured against a window sill, having a base portion adapted to lie over the window sill, and an upwardly extending vertical leg against which a side of said channel is located, the base extending underneath the channel, and a bar bearing at one end against said tensioning member at a distance from said channel and at its other end extending over the open upper side of the channel and adapted to bear against a lower bar element receivable in said channel and to which element a screen, fixed at its upper end, is adapted to be secured, the bar element being secured to the lower end of the screen, and means connected with the base of said tensioning member operatively associated with said bar for forcing the free end of said bar downwardly toward the open upper side of said channel and force said bar element into said channel.

2. A structure as defined in claim 1, the side of said channel lying against said vertical leg of the tensioning member extending above said leg, and at its upper end portion having a bead extending lengthwise thereof away from said vertical leg of the tensioning member over the upper side of the channel.

3. A structure as defined in claim 1, said means connected to the base of the tensioning member comprising, a threaded screw having a head below the base and extending upwardly through and above said bar, and a nut at the upper end of the screw.
